UNITED STATES PATENT OFFICE.

JAMES KEMP, OF DELHI, NEW YORK.

ANIMAL-TRAP.

SPECIFICATION forming part of Letters Patent No. 351,923, dated November 2, 1886.

Application filed April 1, 1886. Serial No. 197,433. (No model.)

To all whom it may concern:

Be it known that I, JAMES KEMP, of Delhi, in the county of Delaware and State of New York, have invented a new and Improved 5 Animal-Trap, of which the following is a full, clear, and exact description.

My invention relates to the construction of a trap of that type wherein two serrated jaws are thrown together by the action of an apertured spring; and the invention consists of an 10 improved form of tripping mechanism, to be hereinafter described, and specifically pointed out in the claims.

Reference is to be had to the accompanying 15 drawings, forming a part of this specification, in which similar letters of reference indicate corresponding parts in both the figures.

Figure 1 is a plan view of my improved animal-trap; and Fig. 2 is a sectional view of 20 the same, taken on line $\alpha\alpha$ of Fig. 1.

In the drawings, A A' represent the jaws of the trap, which, as usual, are provided with serrated edges $a a'$ and pivotally connected with standards $b b$, that are rigidly fixed to the 25 base plate or strip B. These jaws are, as usual, guided by a slotted spring, C, arranged as clearly shown in Fig. 1. The plate or strip B is provided with an arm, D, which extends at right angles from the plate or strip B, and is 30 provided with two lugs, e e, in which there are formed recesses arranged to receive and hold the trunnions $e e$ of a rocking plate, E, formed with a central slot or recess, f, in which the jaw A rests when opened to the position

shown in Fig. 1 to set the trap, the jaw being 35 held in the open position by a pin, g, which projects from the plate E above a pin, h, that extends from the outer face of the jaw A, and the plate E is held in the vertical position in which it is shown in the drawings by a stud or 40 button, k, that is carried by the trapping-lever H, said lever being pivotally mounted on standards $l l$.

Such being the general construction of the parts, it will be seen that when the pan K of 45 the lever H is depressed the stud k will be raised above the plate E, so that the spring C will be free to act to throw the plate E over and close the jaws A A'.

Having thus fully described my invention, 50 what I claim as new, and desire to secure by Letters Patent, is—

1. In a trap, the combination, with the jaws and their spring, of a trapping-lever carrying a button, k, a rocking plate, E, carrying a pin, 55 g, and a pin, h, carried by one of the jaws, substantially as described.

2. In a trap, the combination, with the jaws and their spring, of a trapping-lever, a rocking plate, E, normally upheld by the trapping-lever and carrying a pin, g, and a pin, h, carried by one of the jaws, substantially as 60 described.

JAMES KEMP.
